ABSTRACT OF THE DISCLOSURE

A signal transfer circuit having a plurality of storage means each storage means being coupled to a subsequent storage means. A driver circuit is coupled to each storage means and is responsive to information stored in both the storage means to which it is coupled and the next subsequent storage means. The driver initiates the transfer of information from the storage means to which the driver is coupled to the next subsequent storage means when the next subsequent storage means is cleared. The information contained in the last storage means is cleared when such information is accepted by application utilization circuitry.

This invention relates to signal transfer circuits and more particularly to circuit means for transferring an input signal to utilization means whereby information applied to the circuit at a frequency rate above that which the utilization means is capable of accepting is temporarily stored in apertured magnetic cores until the utilization means is ready to accept the information.

In communication circuits, information is often received at varying frequency rates. However, the output circuit or utilization means is usually incapable of receiving information at greater than a fixed frequency rate. Therefore, when bursts of energy at greater than the fixed frequency rate are transmitted to the utilization means, portions of the signal are either erroneously received or entirely lost.

In other applications, information is often applied to a utilization circuit at a time when the circuit is incapable of accepting the applied information. Under these circumstances, it is desirable to provide storage means for the signal whereby the signal may be stored until the utilization circuit again becomes capable of accepting the signal, at which time the signal is automatically transferred from the storage means to the utilization circuit.

Where information is transmitted in discrete bits, a storage means for retaining merely a single bit of information until the utilization means is ready to accept the information is insufficient if many bits of information are transmitted and the utilization means is incapable of accepting bits at a sufficient rate to permit no more than a single bit at a time to be applied to the storage means. Therefore, it is desirable to provide storage means capable of holding as many bits as may be required to be stored prior to acceptance by the utilization means.

Storage means used in information transmittal circuits must transfer information only at the proper times, for correct circuit operation. Such transfer may occur with use of solid state driver circuits, such as transistor circuits, which exhibit inherent leakage currents. This shortcoming may be overcome by use of driver circuits which present an infinite impedance of the driver energy source except when transmittal of information is desired. Information transmittal from each storage means and driver circuit impedance control for each storage means can be achieved automatically in accordance with the remanent condition of each subsequent storage means.

Accordingly, one object of this invention is to provide a signal transfer circuit comprising a plurality of storage

2

stages whereby information is automatically transferred from one clear storage stage to the next subsequent clear storage stage, automatically, until it reaches a utilization means.

Another object is to provide a signal transfer circuit comprising a plurality of storage stages whereby information is automatically transferred from stage to stage until it reaches a stage prior to one retaining stored information, wherein it is then retained.

Another object is to provide a signal transfer circuit comprising a plurality of information storage stages whereby information which is stored in one stage is automatically transferred to the next subsequent storage stage only when the next subsequent stage becomes cleared.

Another object is to provide a signal transfer circuit utilizing a plurality of coupled storage stages and a separate driver coupled to each storage stage for sensing the condition of the next subsequent storage stage only when the subsequent stage is clear.

Another object is to provide a driver circuit for transferring stored information from a first apertured magnetic core to a second apertured magnetic core when the second core is in the clear condition.

Another object is to provide a driver circuit for a first apertured magnetic core whereby a capacitor discharge is coupled through a contact of a relay responsive to the remanent magnetic state of a subsequent magnetic core for driving information out of the first magnetic core when the subsequent magnetic core is clear.

Another object of this invention is to provide a driver circuit for apertured magnetic cores whereby stored information in each core is represented by the set state of said core and a capacitor discharge is utilized for clearing the set core through contacts of relays responsive to the set condition of said core and a clear condition of a subsequent core.

The invention contemplates a plurality of storage means, each said means being coupled to a subsequent storage means. A driver circuit is coupled to each storage means and is responsive to information stored in both the storage means to which it is coupled and the next subsequent storage means. The driver initiates transfer of information from the storage means to which said driver is coupled, to the next subsequent storage means when the next subsequent storage means is cleared.

The foregoing and other objects and advantages of the invention will become apparent from the following detailed description when read in conjunction with the accompanying drawings, in which:

FIG. 1 is a functional block diagram of the novel signal transfer circuit.

FIG. 2 is a schematic diagram of a first embodiment of the novel signal transfer circuit.

FIG. 3 is a schematic diagram of a second embodiment of the novel signal transfer circuit.

FIG. 4 is a schematic diagram of a third embodiment of the novel signal transfer circuit.

Turning now to FIG. 1 for a general description of the system, there is shown a plurality of drivers, chosen for illustrative purposes only, to be four, and a plurality of storage means, also chosen to be four. Each driver drives a single storage means. Each driver, moreover, is responsive to the condition of the storage means to which it is coupled and to the next subsequent driver. Each storage means couples an input signal to the next subsequent storage means. Acceptance means are coupled to the final driver stage for control thereof in response either to an external signal or the condition of the output circuit. Means are provided for coupling an input signal to the first storage means, and means are also provided for coupling a trigger signal to the first driver stage.

In operation, assume an input signal is applied to the first storage means. When a trigger signal is thereafter applied to the first driver, the first driver being responsive to the condition of the second storage means via the second driver circuit senses that the second storage means is clear. It therefore couples a drive signal to the first storage means, thus transferring information stored in the first storage means to the second storage means. When the information is stored in the second storage means the second driver, being responsive to the condition of the third storage means via the third driver, senses the clear condition of the third storage means and couples a drive pulse to the second means, thereby transferring information stored in the second storage means to the third storage means. Similarly, the third driver then transfers information stored in the third storage means to the fourth storage means. When information is stored in the fourth storage means, the fourth driver, being responsive to the condition of the acceptance means, provides an output signal from the fourth storage means containing the stored information upon receipt of a signal from the acceptance means. The acceptance means signal may be made to occur in response to the condition of the circuit to which the output signal is coupled, or it may be made to occur in response to an externally applied signal.

If no signal is provided from the acceptance means when information is stored in the fourth storage means, the fourth driver does not produce a drive pulse for transferring the information to the output circuit. If thereafter a second signal should be applied to the first storage means, the signal is transferred as previously described, as far as the third storage means. When information is stored in the third storage means, the third driver senses the condition of the fourth storage means through the fourth driver. Since information is now stored in the fourth storage means, it cannot accept information from the third storage means. Thus, the third driver does not produce a drive pulse for transferring information from the third storage means to the fourth storage means. Likewise, a following input signal can only be transferred as far as the second storage means, wherein it is then stored. A subsequent input signal can only be stored in the first storage means.

When the acceptance means provides a signal to the fourth driver, the fourth storage means receives a drive pulse from the fourth driver, thereby transferring its information to the output. The third driver then senses the clear condition of the fourth storage means, and provides a signal for driving information from the third storage means to the fourth storage means. The third storage means is thereby cleared and the second driver then produces a transfer of information stored in the second storage means to the third storage means in a similar fashion. Likewise, the first driver then produces a transfer of information stored in the first storage means to the second storage means. This leaves the first storage means in a clear condition, ready to accept another input signal. Moreover, when the fourth driver receives another signal from the acceptance means, the fourth storage means again produces an output, the third storage means transfers its stored information to the fourth storage means, and the second storage means transfers its stored information to the third storage means. This leaves the first and second storage means in a clear condition, ready to accept new information.

Although the system is shown having four storage means and four drivers, it should be obvious to those skilled in the art that any number of storage means and drivers may be used, as long as each storage means is driven by a separate driver. Such system would be desirable where output circuit information can be accepted only at a predetermined rate, while information is applied in bursts at a rate in excess of the rate at which the output circuit can accept the information.

Turning now to FIG. 2, for a detailed description of the first embodiment of the invention, there is shown a plurality of storage means comprising apertured magnetic cores C1-C4. Each core has an output minor aperture 1-4, respectively. Moreover, cores C2-C4 have second output minor aperture 5-7, respectively, through which a radio frequency signal from an R.F. signal generator 8 is coupled.

Each of a plurality of relays R1-R4 is connected in series with a prime signal coupled respectively through output minor apertures 1-4 of respective cores C1-C4. Each output minor aperture 5-7 is coupled to a relay R5-R7, respectively, through series-connected capacitors 9-11, respectively. Diodes 12-14 are parallel-connected across relays R5-R7, respectively. Contacts 15-17 of relays R5-R7, respectively, are connected in series with and control energization of relays R2-R4, respectively, thereby also controlling priming of minor apertures 2-4 of cores C2-C4, respectively.

Each core C1-C4 is cleared by a signal passed through its major aperture from a front contact 18-21 of a relay R1-R4, respectively. The clear pulse for each of cores C1-C4 respectively is applied through a series circuit comprising a resistor 22-25, a forward-connected diode 26-29, and an inductor 30-33, respectively. The clear pulse for each of cores C1-C4 consists of current produced by the discharge of energy storage means comprising charged capacitors 34-37 respectively, through a back contact 38 of relay R2, a back contact 39 of relay R3, a back contact 40 of relay R4 and back contact 21 relay R4, respectively. Moreover, cores C1-C4 can receive their respective clear signals only when front contacts 18-21 of relays R1-R4, respectively, are closed. Thus, each clear pulse is passed through a circuit responsive to the remnant magnetic state of a pair of adjacent cores.

The circuit permits relays R1-R4 to exhibit contact bounce in clearing the cores without producing an adverse effect on circuit operation, since a pulse duration on the order to two microseconds is sufficient in order to clear any of cores C1-C4. Tests have shown that the first rebound of a relay contact upon closing, due to closure impact reaction, does not occur until approximately five hundred microseconds after initial contact closure has occurred; that is, once the contact is initially closed, it remains closed for approximately five hundred microseconds prior to bouncing open. Since a pulse of approximately two microseconds duration is required to clear a core, the RLC time constants of resistor 22, inductor 30 and capacitor 34, resistor 23, inductor 31 and capacitor 35, resistor 24, inductor 32 and capacitor 36, and resistor 25, inductor 33 and capacitor 37 are each chosen to produce an almost critically damped pulse which is far shorter in duration than five hundred microseconds. Such pulse duration is preferably chosen to be on the order of two microseconds. Therefore, before the first bounce of the relay contact occurs, momentarily opening its circuit, the capacitor coupled thereto is fully discharged, so that when the contact recloses after the first bounce, current cannot resume flowing through the major aperture of the core through which the RLC circuit is coupled.

Each capacitor 34-37 acquires a charge through a resistor 41-44, respectively, in series with front contact 38 of relay R2, front contact 39 of relay R3, front contact 40 of relay R4, and front contact 21 of relay R4, respectively. Resistors 41-44 control the rate at which capacitors 34-37 charge, and thereby also serve to limit power supply surges at the instant any of the capacitors begins to charge. Resistors 22-25 and inductors 30-33 comprise pulse forming networks which shape the discharge current waveforms of respective capacitors 34-37. Because of the short duration of pulses provided by capacitors 34-37, the pulse forming networks provide high output impedances which cause the capacitors to appear as constant current sources during the intervals in which

they provide pulses to the cores. Diodes 26-29 serve to eliminate any negative current overshoot through the clear circuits which is created in the event the current pulses through the clear circuits are slightly underdamped, as evidenced by a slight oscillation at the end of each of the current pulses.

Input information is coupled to core C1 in a fashion to alter the remanent magnetic state of the core through the leg between the major aperture and output minor aperture 1. Output information from the leg outside the minor aperture of core C1 is coupled to core C2 in a fashion to alter the remanent magnetic state of core C2 through the leg between the major aperture and output minor aperture 2. Output information is coupled from the leg outside output minor aperture 2 or core C2 to core C3 in a fashion to alter the remanent magnetic state of core C3 in the leg between the major aperture and output minor aperture 3. Output information is coupled from the leg outside output minor aperture 3 of core C3 to core C4 in a fashion to alter the remanent magnetic state of the core in the leg between the major aperture and output minor aperture 4. Output information is coupled from the leg outside output minor aperture 4 of core C4 to a utilization means 45, which comprises any circuit or device requiring information of the form applied to the novel coupling circuit.

When input current is applied to a multi-aperture core so as to thread the leg located between the major aperture and a minor aperture, the core is switched to its set state. When the core is thereafter destructively cleared, no output pulse is produced on the input, or set winding, since the magnetic polarity in the leg between the major and minor apertures reverses only when the core is switched from the clear to the set state and from the set to the primed state, as is well-known in the art. Thus, undesirable back transfer of pulses is avoided during clearing of the core. Moreover, since priming is accomplished with a slow rise time direct current, the core is switched slowly from the set to the primed state, thus minimizing back transfer of pulses during the priming operation.

Acceptance means 46 is coupled between the capacitor 37 and contact 21 of relay R4, and may be any circuit controlling discharge of capacitor 37 through contact 21, such as a gating circuit, a switch, a relay contact, etc. The acceptance means may be made responsive either to an external control signal, or to the utilization means. In this respect, a dotted line is shown coupling the utilization means to the acceptance means, indicating control of the acceptance means in this embodiment is in response to the condition of the utilization means.

Each of the relays R5-R7 is energized during the interval in which the core coupled to the relay is set. This energization is achieved by means of radio frequency energy induced in the circuit coupling the relay to the core, by the signal from R.F. signal generator 8. Thus, when the induced signal polarity is in the forward conducting direction of the diode connected in parallel with the relay, the capacitor acquires a charge. When the induced signal polarity reverses, current flows through the relay rather than the diode, since current flow direction is now in the reverse conducting direction of the diode. Moreover, the voltage stored on the capacitor adds to the voltage produced from the output minor aperture of the core, so that a large voltage is produced across the relay. The relay then energizes and remains energized as long as the core to which it is coupled remains set.

In operation, assume that no information is stored in the transfer circuit. Under such circumstances, cores C1, C2, C3 and C4 are clear. Capacitor 34 is fully charged through resistor 41 and back contacts 18 and 38 of relays R1 and R2, respectively. Likewise, capacitor 35 is fully charged through resistor 42 and back contacts 19 and 39 of relay R2 and R3, respectively, capacitor 36 is fully charged through resistor 43 and back con-

tacts 20 and 40 of relays R3 and R4, respectively, and capacitor 37 is fully charged through resistor 44, back contact 21 of relay R4 and acceptance means 46.

Assume now that an input signal is applied to the input terminals of the transfer circuit. This causes core C1 to become set. Assume that next a positive trigger pulse is applied to the trigger terminal of the circuit, momentarily energizing relay R1. Although the trigger circuit is herein depicted as receiving an external trigger pulse, the relay R1 energizing pulse could alternatively be obtained automatically when core C1 becomes set, in a fashion similar to that for energizing relays R2, R3 and R4 from relays R5, R6 and R7, respectively, when cores C2, C3 and C4, respectively, are set.

Triggering of relay R1 serves to prime minor aperture 1 of core C1 with a slow rise time direct current, due to the large inductance of the relay winding. Since a finite time interval exists between energization of the relay and closing of its front contacts, core C1 is primed prior to closing of front contact 18. This provides a discharge path for capacitor 34 through back contact 38 of relay R2 and front contact 18 of relay R1 through the major aperture of core C1. The capacitor discharge causes core C1 to clear, producing an output pulse on the coupling loop through minor aperture 1 which sets core C2. Upon setting of core C2 relay R5 becomes energized, closing its front contact 15 and thereby priming minor aperture 2 of core C2. Moreover, relay R2 energizes, closing its front contacts 19 and 38. Front contact 38 permits capacitor 34 to again resume charging. Closing of front contact 19 permits capacitor 35 to discharge through back contact 39 of relay R3 and front contact 19 of relay R2, through the major aperture of core C2, thereby clearing the core and producing an output pulse on the coupling loop threading minor aperture 2 of core C2, in turn setting core C3. Upon clearing of core C2, relay R5 deenergizes, deenergizing relay R2.

When core C3 becomes set, relay R6 energizes, thereby energizing relay R3 and priming minor aperture 3 of core C3. Front contact 20 of relay R3 then closes, permitting capacitor 36 to discharge through back contact 40 of relay R4 and front contact 20 of relay R3, through the major aperture of core C3. This clears core C3, causing relay R6 to deenergize and core C4 to become set. When core C4 becomes set, relay R7 energizes, causing minor aperture 4 of core C4 to become primed and relay R4 to become energized, closing its front contact 21. Assuming the acceptance means is in condition to permit passage of the signal from the transfer circuit to the utilization means, capacitor 37 discharges through the acceptance means and front contact 21 of relay R4, through the major aperture of core C4, causing an output signal to be produced on the coupling loop joining minor aperture 4 and utilization means 45. Thus, the utilization means receives the signal initially applied to the input terminals of the transfer circuit. Furthermore, when core C4 clears, relay R7 deenergizes. The transfer circuit once again has no information stored therein, and is prepared to accept a new input signal.

Assume now that when the input signal is coupled through the circuit to core C4, the acceptance means is not conditioned to permit transfer of the charge stored on capacitor 37 through the major aperture of core C4. A single bit of information is therefore stored in core C4, and cannot be transferred to the utilization means until the acceptance means completes the circuit from capacitor 37 to front contact 21 of relay R4. If during the interval in which the acceptance means prevents transfer of the signal from core C4 to the utilization means, a new input signal is applied to the transfer circuit and a new trigger pulse is also applied to the circuit, the signal is transferred from core C1 to core C2 and then to core C3, in a manner similar to that previously explained. However, when the signal reaches core C3, setting the core and thereby energizing relay R6, minor

aperture 3 of core C3 becomes primed and relay R3 closes its front contact 20. Since core C4 is set, relay R7 is energized, thereby maintaining relay R4 energized. Front contact 40 of relay R4 is therefore open, preventing capacitor 36 from discharging through front contact 20 of relay R3, thereby preventing core C3 from becoming cleared. Thus, a first bit of information is stored in core C4, and a second bit of information is stored in core C3.

In the event still another input signal is applied to the transfer circuit, it can travel only as far as core C2, which then becomes set; however, for reasons similar to those previously explained, capacitor 35 cannot discharge through front contact 19 of relay R2, thereby preventing core C2 from becoming cleared. If still another input signal representative of another bit of information is applied to the transfer circuit, core C1 will become set and will be prevented from clearing through capacitor 34 because back contact 38 of relay R2 is now open.

If now acceptance means 46 should momentarily complete a circuit between capacitor 37 and front contact 21 of relay R4, core C4 becomes cleared, thereby coupling the information stored therein to utilization means 45. Upon clearing of core C4, relay R7 deenergizing relay R4. This closes back contact 40 of relay R4, permitting capacitor 36 to discharge through front contact 20 of relay R3 and clear core C3 through its major aperture, transferring information from core C3 to core C4. Likewise, back contact 39 of relay R3 then closes, permitting capacitor 35 to discharge through front contact 19 of relay R2 and clear core C2, thereby setting core C3. This in turn permits capacitor 34 to discharge through back contact 38 of relay R2 and front contact 18 of relay R1, thereby clearing core C1 and causing it to transfer its information to core C2. Core C1 is now clear and prepared to accept a new bit of information.

If the acceptance means again completes a circuit between capacitor 37 and front contact 21 of relay R4, core C4 again produces an output pulse, and information stored in core C3 is transferred to core C4, while information stored in core C2 is transferred to core C3. Thus, each core and the relays coupled thereto function as a separate buffer storage stage in the signal transfer circuit.

Turning now to FIG. 3 there is shown a modification of the circuit of FIG. 2, wherein back transfer of core output pulses is prevented by utilization of a separate input aperture in each of the cores and by coupling prime current through each input aperture in order to slowly switch flux direction in the core leg outside the input aperture prior to clearing the core, thereby preventing a sharp flux direction change in that leg which could induce a voltage in a set winding coupled thereon. Thus, the transfer circuit of FIG. 3 shows use of four multi-aperture cores C11-C14, for storage of information. Each core has an input minor aperture 61, 63, 65 and 67, respectively, and an output mirror aperture 62, 64, 66 and 68, respectively. Cores C12-C14 moreover have third minor apertures 69-71, respectively, for producing radio frequency energy indicative of the remanent magnetic state of the core. Driver relay R11-R14 are connected in a fashion similar to drive relays R1-R4 of FIG. 2, with the exception that energization current for each driver relay is coupled through both input and output minor apertures of the core with which the relay is associated. This current serves to prime both minor apertures through which it is coupled.

Operation of this circuit is quite similar to that of the circuit of FIG. 2. Here however, when a signal is applied to the circuit input terminals, core C11 becomes set by passage of input current through minor aperture 61. When relay R11 is thereafter triggered, a signal is coupled from output minor aperture 62 of core C11 to input minor aperture 63 of core C12, thereby setting core C12. In a manner similar to that explained in conjunction with

FIG. 2, relay R12 then becomes energized, coupling prime current through minor apertures 63 and 64 of core C12. When a clear pulse is thereafter passed through the major aperture of core C12, an output pulse is coupled from minor aperture 64 of core C12 to input minor aperture 65 of core C13, setting core C13. Since magnetic flux direction in the core leg outside minor aperture 63 of core C12 has previously been switched slowly by current flow through relay R12, no back pulse is coupled from minor aperture 63 of core C12 to minor aperture 62 of core C11. This is because relay R12 adds inductance to the prime circuit, thereby preventing sudden changes of prime current through the minor apertures of the core to which it is coupled. Similar effects are produced on cores C13 and C14 by relays R13 and R14, respectively. The remainder of operations performed by the circuit FIG. 3 are performed in identical fashion with the operations performed by the circuit of FIG. 2.

Turning next to FIG. 4, there is shown a signal transfer circuit wherein each storage means comprises a column of apertured magnetic cores, and is therefore capable of storing a large number of bits of information. Driving circuits for priming and clearing the cores in FIG. 4 are identical to the driving circuits shown in FIG. 2. 25 The circuit accommodates a plurality of inputs and provides a plurality of outputs.

The circuit is shown having four inputs, input 1-input 4. Not every input must receive a signal, since a composite signal may be applied to the circuit wherein presence or 30 absence of a pulse is used to denote information, that is, a pulse code modulated signal can be applied to the circuit instead of merely a single pulse.

The final storage means in this embodiment of the circuit are connected so as to provide additional output 35 information in accordance with the input code. To achieve this result, each core of the fourth column of core utilizes two output minor apertures. Thus, core C400 has a pair of output minor apertures 100 and 101, core C401 has a pair of output minor apertures 102 and 103, core C402 40 has a pair of output minor apertures 104 and 105, and core C403 has a pair of output minor apertures 106 and 107. Each of the aforementioned cores also utilizes a separate input minor aperture, 108-111, respectively. Relay R7 is coupled through a minor aperture 112 of core C400 45 for energization by radio frequency energy from a signal generator 8 when core C400 is set.

Acceptance means are herein shown, for illustrative purposes, as a relay R9 having a front contact 114. This contact provides current through front contact 21 of relay 50 R4 and either front or back contact 115 of a direction control relay R8, depending upon whether relay R8 is energized or deenergized from an external terminal 113, through the output minor apertures of cores C400-C403. Thus, when front contacts 114 and 21 are closed, if relay 55 R8 is deenergized, output minor apertures 101, 103, 105 and 107 of cores C400-C403, respectively, are primed, while if relay R8 is energized, minor apertures 100, 102, 104 and 106 of cores C400-C403, respectively, are primed. Thus, upon deenergization of relay R8, outputs 60 1R, 2R, 3R, and 4R provide output information, while when relay R8 is energized, outputs 1N, 2N, 3N and 4N provide output information.

A relay R10 is coupled to the prime windings of cores C400-C403. When relays R9 and R4 are both energized, 65 relay R10 is energized through front contacts 114 and 21. Front contact 116 of relay R10 then closes, causing discharge of capacitor 37 through the major apertures of cores C400-C403, thereby providing readout of the final stage of the circuit.

Energization for relay R4 is here used to prime only the input minor apertures 108-111 of cores C400-C403, respectively, in order to avoid back transfer of pulses from the aforementioned cores upon clearing of the cores.

In operation, assume a pulse code modulated signal 75 is applied to inputs 1-4 such that, for example, input 1,

input 3 and input 4 each receives a pulse while input 2 receives no pulse. Thus, cores C100, C102 and C103 are set, while core C101 remains clear. When a trigger signal is thereafter applied to relay R1, output minor apertures 117, 119 and 120 of cores C100, C102 and C103 becomes primed. Closing of front contact 18 of relay R1 then causes capacitor 34 to discharge through the major apertures of cores C100-C103, providing readout from these cores. This causes cores C200, C202 and C203 to become set, while core C201 remains clear. Relay R5 then causes energization of relay R2, and the information stored in cores C200-C203 is transferred to cores C300-C303, respectively, when capacitor 35 discharges through front contact 19 of relay R2, clearing cores C200-C203. This causes cores C300, C302 and C303 to become set, while cores C301 remain clear.

Upon setting of core C300, relay R6 energizes, causing relay R3 to energize and close its front contact 20. This causes discharge of capacitor 36 through front contact 20 of relay R3 and the major apertures of cores C300-C303, causing transfer of set pulses from cores C300, C302 and C303 to cores C400, C402 and C403, respectively. Since core C400 is now set, relay R7 energizes, causing relay R4 to energize and close its front contact 21. Moreover, if relay R8 is energized, closing its front contact 115, and if the acceptance input terminals of relay R9 are energized, front contact 114 of relay R9 closes and minor apertures 100, 104 and 106 of cores C400, C402 and C403 respectively become primed. Furthermore, relay R10 becomes energized, closing its front contact 116. This causes discharge of capacitor 37 through the major apertures of cores C400-C403, producing the applied pulse code modulated signal on outputs 1N-4N, whereby output 1N, output 3N and output 4N each provide an output voltage and output 2N provides no output voltage.

If the acceptance input terminals of relay R9 are not energized, contact 114 of relay R9 is open, preventing priming of the output minor apertures of cores C400-C403 and preventing energization of relay R10, thereby also preventing discharge of capacitor 37 through front contact 116 of relay R10. Under these circumstances, a signal applied to the circuit travels as far as cores C400-C403 and then remains stored in the aforementioned cores until the acceptance input terminals of relay R9 are energized, providing readout of the signal.

In the event the acceptance input terminals of relay R9 are not energized and a pulse code is stored in cores C400-C403, then, if a second input code is applied to inputs 1-4, the incoming coded signal is transferred from cores C100-C103 to cores C200-C203 and thence to cores C300-C303, wherein it is stored. The signal cannot be transferred from cores C300-C303 since relay R4 is energized through front contact 17 of relay R7, thereby holding open its back contact 40, preventing capacitor 36 from discharging through the major apertures of cores C300-C303. In like fashion, a third coded signal can be stored in cores C200-C203 and a fourth coded signal can be stored in cores C100-C103.

In the event a signal stored in cores C400-C403 is transferred out by energization of relay R9, relay R7 de-energizes, deenergizing relay R4 and permitting back contact 40 of relay R4 to close. This permits capacitor 36 to discharge through the major apertures of cores C300-C303, thereby transferring the signal stored in the third storage means to cores C400-C403. Likewise, the code stored in the second storage means is then transferred to the third storage means upon discharge of capacitor 35 through the major apertures of cores C200-C203, and the coded signal stored in the first storage means is transferred to the second storage means upon discharge of capacitor 34 through the major apertures of cores C100-C103.

Assuming the acceptance input terminals of relay R9 remain energized, assume the signal now stored in the

fourth storage means is coded so that core C403 is clear while cores C400-C402 are set. Assume further that relay R8 is deenergized, thereby closing its back contact 115. When relay R4 energizes, its front contact 21 closes, priming minor apertures 101, 103 and 105 of cores C400, C401 and C402. This causes energization of relay R10, which closes its front contact 116, thereby clearing cores C400-C403. A coded output signal then appears on outputs 1R-4R, and comprises a voltage pulse on outputs 1R, 2R and 3R, and no voltage pulse on output 4R.

Thus, there has been shown a signal transfer circuit comprising a plurality of storage stages whereby information is automatically transferred from one stage through a subsequent clear stage, until it reaches the circuit output terminals or a clear storage stage just prior to a stage retaining stored information, in which case it is stored in the clear stage until the information stored in the next subsequent stage is transferred ahead. The circuit utilizes separate drivers coupled to each separate storage stage for sensing the condition of a next subsequent storage stage and driving information from the stage in which it is stored into the next subsequent storage stage only when the next subsequent stage is clear. Moreover, the driver circuits are simple and utilize few circuit components; yet each is responsive to the remanent magnetic state of the next subsequent core, so as to prevent an attempt at transfer of stored information from one core to a subsequent core which it already set and therefore unable to accept a new set pulse.

Although several embodiments of the present invention have been described, it is to be specifically understood that these forms are selected to facilitate in disclosure of the invention rather than to limit the number of forms which it may assume; various modifications and adaptations may be applied to the specific forms shown to meet requirements of practice, without in any manner departing from the spirit or scope of the invention.

What is claimed is:

1. A signal transfer circuit comprising a plurality of storage means, each said means being coupled to a subsequent storage means, and a separate driver circuit coupled to each storage means and responsive to information stored in the next subsequent storage means for driving information into the next subsequent storage means.

2. The circuit of claim 1 wherein the storage means comprises a plurality of apertured magnetic cores.

3. A circuit for controlling passage of a signal therethrough in accordance with circuit conditions comprising a plurality of apertured magnetic cores, each core having an input and an output, means coupling the output of each core to the input of a subsequent core, a separate driver circuit coupled to each core for clearing said cores, and means coupling each driver circuit to each subsequent core for controlling operation of said driver in response to the remanent magnetic state of said subsequent core.

4. A signal transfer circuit comprising at least a pair of apertured magnetic cores, each core having an input and an output, means coupling the output of a first core of said pair to the input of the second core of said pair, means coupling an input signal to the first core, means coupling an output signal from the second core, switching means coupled to said pair and responsive to the remanent magnetic state of each core of said pair, and energy storage means coupled to the switching means for providing a clear pulse through the first core only when the first core is set and the second core is clear.

5. A circuit for controlling passage of a signal therethrough in accordance with circuit conditions comprising a plurality of apertured magnetic cores, each core having an input and output, means coupling the output of each core to the input of a subsequent core, switching means coupled to each pair of adjacent cores and responsive to the remanent magnetic state of each prior and subsequent

11

core of said pair, and energy storage means coupled to the switching means for providing a clear pulse through the prior core of said pair when said prior core is set and the subsequent core of said pair is clear.

6. A circuit for controlling passage of a signal therethrough in accordance with circuit conditions comprising a plurality of apertured magnetic cores, each of said cores having input means and output means, means coupling the output means of each separate core to the input means of a subsequent core, and driver means responsive to the remanent magnetic state of each said subsequent core for clearing each said separate core and thereby transferring information to the subsequent core only when the subsequent core is clear.

7. The circuit of claim 6 wherein the driver means for clearing said separate core comprises a first relay, means responsive to the remanent magnetic state of said separate core for controlling energization of the relay, energy storage means, a second relay coupled to said subsequent core, and means coupling clear current through said separate core from said energy storage means through a front contact of the first relay and a back contact of the second relay.

8. The circuit of claim 7 wherein energization current for the first relay is coupled to said separate core for priming said output means.

9. The circuit of claim 7 wherein the means responsive to the remanent magnetic state of said separate core comprises a relay coupled to said separate core and having a front contact coupled to the first relay for energizing said first relay when said separate core contains stored information.

10. The circuit of claim 9 wherein energization current for the first relay is coupled to said separate core for priming said output means.

11. Driver means for a circuit having a plurality of apertured magnetic cores coupled to transfer a signal from one core to a subsequent core comprising a plurality of first relays, means responsive to the remanent magnetic state of each separate core for energizing each of said relays, energy storage means, and means coupling a clear pulse for said one core from said energy storage means through a back contact of the relay energized from the subsequent core and a front contact of the relay energized from said one core for clearing said one core only when said subsequent core is in the clear condition.

12. The driver means of claim 11 wherein each responsive means comprises a second relay coupled to each separate core and having a front contact coupled to the first relay energized from said separate core whereby presence of information stored in the separate core produces actuation of the second relay energized from said core.

13. Driver means for a circuit having a plurality of columns of apertured magnetic cores coupled to transfer a signal from one column to a subsequent column comprising a plurality of first relays, means responsive to the remanent magnetic state of the first core in each column for energizing each of said relays, energy storage means, and means coupling a clear pulse for a single

5 column from said energy storage means through a back contact of the relay energized from the first core of the subsequent column adjacent said single column and a front contact of the relay energized from the first core of said single column for clearing the cores of said single column only when the first core in said subsequent adjacent column is in the clear condition.

10 14. The driver means of claim 13 wherein each responsive means comprises a second relay coupled to the first core in the single column and having a front contact coupled to the first relay energized from the first core in said single column whereby presence of information stored in the first core of the single column produces actuation of the second relay energized from the first core of said single column.

15 15. A circuit for controlling passage of a signal therethrough in accordance with circuit conditions comprising a plurality of columns of apertured magnetic cores, each core having an input and an output, means coupling the output of each core to the input of a subsequent core, a 20 separate driver circuit coupled to the cores in each column for clearing the cores of said column, and means coupling each driver circuit to one core in each subsequent column of cores for controlling operation of said driver in response to the remanent magnetic state of said one core.

25 16. A circuit for controlling passage of a signal therethrough in accordance with circuit conditions comprising a plurality of columns of apertures magnetic cores, each 30 column having an input and an output, means coupling the output of each column to the input of a subsequent column, a separate driver circuit coupled to each column for producing transfer of information out of said column, and means coupling each driver circuit to each subsequent column for controlling operation of said driver in response to information stored in said subsequent column.

35 17. A method of transferring information signals through serially coupled storage means to a utilization 40 circuit comprising the steps of setting a first storage means with the information signal, successively setting each subsequent storage means in accordance with the information signal stored in each prior adjacent storage means only when information stored in the subsequent storage means is cleared, and finally transferring the information signal from the last storage means whenever the utilization circuitry is capable of accepting such information signal.

45 18. The method of claim 17 wherein the storage means comprise multiaperture magnetic cores.
